UNITED STATES PATENT OFFICE.

WILLIAM K. PORTER, OF PITTSBURGH, PENNSYLVANIA.

MILK-BOTTLE CONTAINER.

Application filed June 10, 1925. Serial No. 36,194.

This invention relates to a milk bottle container, and particularly to a construction having an adjustable arrangement of the compartments therein to accommodate articles of different sizes or heights.

In order to prevent the theft of bottles containing milk or other dairy products delivered at a time before the consumer is ready to receive the same, and also to prevent possible contamination by the licking of the bottles by stray animals, it has been found important to provide a container in which the bottles may be locked after delivery.

In prior constructions of this character the compartments are generally of a fixed size or area which frequently prevents the utilization of the full space within the container and does not provide separate compartments for the several articles, particularly if other products than milk are to be delivered. Further, in providing for the automatic locking of the door of the container after an article has been placed therein the latch has previously been controlled by the weight of the article or movement of a part of the container, which often results in uncertainty in the action of the locking device as such weight may vary in the case of different articles delivered.

To overcome these objections I have provided a container having pivoted shelves adapted to vary the capacity of one or more compartments by dividing them into separate compartments in which the shelves support the articles placed therein. I have further provided a lock or latch for the door adapted to be normally freely actuated by a handle when the container is empty and to be positively shifted out of operative relation with the handle and into position for operation by a key through direct engagement with an article placed within the container.

It has also been found that certain foods such as milk and dairy products are seriously affected by extremes of temperature when the container is exposed to the normal temperature and to thus protect the contents a heat insulating filler is disposed between an inner and outer shell which will prevent freezing in winter and the deleterious effect of heat in summer resulting in the souring of milk or softening of butter.

The invention has for an object to provide a novel and improved construction of container comprising an outer casing and an inner casing formed with compartments between which a non-conducting filler is inserted, and comprises a separate body conformed to fit the space between the inner and outer casing.

A further object of the invention is to provide a novel construction of the inner casing having a vertical partition upon which a shelf is pivotally mounted and adapted to be swung from a horizontal to a vertical plane in order to vary the capacity of the compartments with which it is associated.

Another object of the invention is to provide an improved form of locking mechanism involving an oscillatory bolt member having a detent adapted to be normally engaged by a member operated by the handle and also a trip member extending at an angle to the bolt for engagement with an article within the container to oscillate the bolt into position for bringing a second detent into operative relation with the key for actuating the bolt.

Other and further objects and advantages of the invention will be hereinafter set forth and the novel features thereof defined by the appended claims.

In the drawing:

Figure 1 is an elevation of the container;

Figure 2 is a similar view showing a different arrangement of the compartments;

Figure 3 is a detail perspective of the outer casing;

Figure 4 is a similar view of the non-conducting filler;

Figure 5 is a like view of the inner partitioned casing;

Figure 6 is an elevation of the lock;

Figure 7 is an end view thereof;

Figure 8 is a section on line 8—8 of Figure 6;

Figure 9 is a section on line 9—9 of the same figure; and

Figure 10 is a section on line 10—10 of Figure 6.

Like numerals designate corresponding parts throughout the several figures of the drawing.

The container may be formed of any desired size or configuration depending upon

the number of articles which it is desired to ordinarily dispose therein and for the purpose of illustration is herein shown as comprising an outer casing or frame 10 of rectangular shape which is provided with supports 11 at its base adapted to be attached to any desired structure. If desired the container may be supported by other means than the legs 11 at its base. This outer frame is provided with a door or closure 12 having a beveled edge 13 to form a tight joint with the casing and pivotally supported thereon by means of hinges 14.

Within the outer casing the insulated filler 15 is disposed and this comprises a rectangular body conformed to the shape of the container and provided at one side with recesses 16 for the hinges 14 and at the opposite side with a similar recess 17 for reception of the lock keeper 18.

Within the non-conducting filler I dispose the inner casing 19 which is provided at its front edge with an apertured flange 20 for attachment to the casing 10 and at one edge this flange is cut away at 21 to receive the hinge members 14 and at its opposite edge a similar portion 22 is provided for the lock keeper. Centrally within the inner casing 19 a vertical partition 23 is provided having at its upper portion a fixed horizontal shelf 24 which provides a compartment 25 at the upper portion of the container adapted to receive articles such as butter, cheese or other dairy products.

The portion beneath the shelf 24 forms a container 26 adapted to receive a milk bottle of normal size, while at the opposite side of this partition a lower compartment 27 is formed. This compartment is adapted to be sub-divided by means of a shelf 28 pivoted at 29 to the partition and resting upon a stop 30 at the outer wall of the container, such arrangement being shown in Figure 1 as adapted for the reception of two bottles of smaller size. If it be desired to dispose two larger bottles in the compartments this shelf 28 may be raised into vertical position, as shown in Figure 2, while a further shelf 31 pivoted at 32 to the shelf 24 may be swung into horizontal position against the stop 33. The result of such an adjustment utilizes the area of the upper compartment 25 to receive additional articles. With the parts in the position shown in Figure 1 this adjustable shelf 31 is disposed in vertical position against a stop member 34 at the top of the casing.

The door or closure 12 is provided with a handle 35 the shank of which carries an operating lug 36 which is normally disposed in contact with a detent 37 at the inner end of the locking bolt 38. This bolt is mounted to slide upon the plate 39 by means of the lateral apertured extensions 40 and 41 therefrom. The bolt is threaded into the lock

head 42 and capable of an oscillatory movement. This movement is imparted to the bolt by means of an angularly disposed arm 43 secured at the end 44 of the bolt and provided with the contact finger 45 adapted to engage a bottle or other article within the casing when the door is closed and thus oscillate the bolt from its position shown in Figure 6 to disconnect the handle lug, as shown by dotted lines in Figure 7.

In such movement a further detent 46 upon the bolt is brought into position to be actuated by a key 47 for withdrawing the bolt from its keeper. This key may be supported in any desired manner, for instance by means of a bearing 48 formed from the plate 39 which is also bent at 49 to form a stop for the retracting movement of the bolt when restored into operative relation with the handle lug. This retracting movement is effected by means of a spring 50 surrounding the bolt and performing the double function of projecting the bolt and also restoring it after oscillation. The spring has its end 51 passed through an aperture in the bolt for connection thereto and its opposite end 52 suitably secured to the plate 39.

With the construction shown it will be seen that the compartments of the container may be adjusted in capacity or area by means of the pivoted shelves therein, while the contents being of a perishable nature are protected against extremes of temperature by means of the non-conducting filler which is inserted as a unit between the inner and outer casings. The lock mechanism also provides for its free operation by the handle when the container is empty and for its disconnection from the handle when the door is closed and the arm thereon contacts with an article within the container. When in such shifted position the lock can only be operated by the key but as soon as the door is reopened the parts are automatically restored by the lock spring.

The invention thus presents a simple, efficient, and economically manufactured form of container adapted to be automatically locked on the closing of the door when a compartment thereof has received an article to engage the lock operating means.

While the specific construction of the several parts has been shown and described, the invention is not confined thereto as changes and alterations may be made without departing from the spirit of the invention as defined by the following claims.

Having thus described my invention, what I claim as new and desire to secure by Letters Patent is:

1. In a container, a casing provided with a vertical partition forming separate compartments and a shelf movably connected at one side of said partition to swing from a vertical to a horizontal position and sub-

divide one compartment of the container into separate superposed compartments each adapted to receive an article.

2. In a container, a casing provided with 5 a vertical partition and a shelf pivoted at the upper end thereof to form a continuation of the partition and adapted to swing from a vertical plane into a horizontal plane to engage a stop upon a parallel wall of the 10 casing and provide a compartment above said partition.

3. In a container, a casing provided with a vertical partition, a fixed horizontal partition at the top thereof, a shelf pivoted to 15 said horizontal partition to form a continuation thereof, and a shelf pivoted to the vertical partition to engage an opposite wall of the casing.

4. In a container, a casing adapted to receive an article, a pivoted closure, a lock device having separate operating faces to be 20 selectively actuated by a handle or key, said device being disconnected from the key and operable by the handle when the compartment is empty, and means upon said device disposed to directly engage an article in 25 the casing and shift the device to disconnect the handle while connecting the key to operate the lock.

5. In a container, a casing adapted to receive an article, a pivoted closure, a lock device having separate operating faces to be 30 selectively actuated by a handle or key, said device being disconnected from the key and operable by the handle when the compartment is empty, means upon said device disposed to directly engage an article in the 35 casing and shift the device to disconnect the handle while connecting the key to operate the lock, and means to automatically restore 40 the lock device into cooperative relation with the handle.

6. In a container, a casing adapted to receive an article, a pivoted closure, a lock 45 mounted thereon and comprising a recipro-

cating oscillating bolt having operating faces disposed at an angle to each other, a handle having a lug engaging one of said faces, a support for a key to permit the same to engage the other face, and an arm from 50 said bolt for oscillating the same.

7. In a container, a casing adapted to receive an article, a pivoted closure, a lock mounted thereon and comprising a reciprocating oscillating bolt having operating 55 faces disposed at an angle to each other, a handle having a lug engaging one of said faces, a support for a key to permit the same to engage the other face, an arm from said bolt for oscillating the same, and a contact head on said arm adapted to engage an article within the container when the door is closed.

8. In a container, a casing adapted to receive an article, a pivoted closure, a lock 60 mounted thereon and comprising a reciprocating oscillating bolt having operating faces disposed at an angle to each other, a handle having a lug engaging one of said faces, a support for a key to permit the 65 same to engage the other face, an arm from said bolt for oscillating the same, and a spring connected to said bolt and a fixed point for projecting the bolt and also tensioning an operating face thereon into alignment with the handle lug.

9. In a container, a casing adapted to receive an article, a pivoted closure, a plate mounted thereon, a bolt pivoted upon said plate and provided with detents disposed at 70 an angle to each other, a handle member provided with a lug disposed to normally engage one of said detents, and an arm projected at an angle from said bolt and adapted to shift the same to disconnect the detent 75 from said lug and present the other detent into position for operation by a key.

In testimony whereof I affix my signature.

WILLIAM K. PORTER.
